UNITED STATES PATENT OFFICE.

FRANCIS H. RICHARDS, OF SPRINGFIELD, MASSACHUSETTS.

BUTTON-FASTENER-SETTING MACHINE.

SPECIFICATION forming part of Letters Patent No. 310,541, dated January 6, 1885.

Application filed September 13, 1884. (No model.)

To all whom it may concern:

Be it known that I, FRANCIS H. RICHARDS, a citizen of the United States, residing at Springfield, county of Hampden, State of Massachusetts, have invented certain new and useful Improvements in Button-Fastener-Setting Machines, of which the following is a specification, reference being had to the accompanying two sheets of drawings, forming a part of the same, in which—

Figure 1 is a plan view of a machine embodying my invention. Fig. 2 is an elevation of the right-hand side of the same. Fig. 3 is a vertical sectional front elevation, the section being taken in line X X, Fig. 1. Fig. 4 is a vertical longitudinal section near the center of the machine, of the front part thereof. Fig. 5 is an enlarged view of a part of Fig. 4, showing some of the parts in a different position. Fig. 6 is a sectional view of the magazine in line Y Y, Fig. 2, showing a button-fastener rightly placed therein. Fig. 7 is a similar view showing said fastener wrongly placed therein. Fig. 8 is an end view of the magazine. Fig. 9 shows a plan view of the rear part of the frame and a sectional view of the same in line z z. Fig. 10 is a sectional view in line y y, Fig. 2, showing the plunger-carrier in its working position. Fig. 11 is a similar view showing the same part in a different position.

Similar letters refer to similar parts throughout the several views.

This invention relates to machinery especially adapted for setting or inserting into shoe-uppers that kind of button-fasteners known in the market as "Kempshall's one-prong button-fasteners." This fastener consists of a flat piece of metal, substantially as shown at F in Figs. 6 and 7, having a prong, U, and a bar or head, W, at about right angles thereto, preferably so made relative to said prong that when this is set in a shoe, it being bent into a hook through the eye of the button, the button will pull centrally on said head.

The invention has for its object to furnish a convenient and efficient machine, adapted to be operated by foot-power, in which a supply of fasteners are fed from a magazine to a driving mechanism, whereby they may be in-

serted one at a time into a shoe-upper, the prong of the fastener passing through the eye of a button suitably held above the said shoe-upper; and then clinching to hold said button thereto.

For the attainment of this object the invention consists in certain devices and combinations of mechanism which I will first describe in connection with the drawings, and afterward point out in the claims.

In the drawings, A is the frame of the machine, which is herein shown of a box-shaped form, but which may be constructed in any other manner suitable to support the parts secured thereon. At its front end, which is at the left hand in Figs. 1 and 2, the frame has a vertical extension or flange, A', and is formed to receive the front plate, P, and supports one end of guide-rod G, and secured on its upper surface there is an upright, A², carrying presser-arm N and one end of the magazine-holder H. In said surface there is a groove, G², and openings through which pass links L. At the rear end of the frame a bracket, A³, carries the outer end of the said guide-rod.

P is the front plate, which is secured to the front end of frame A by screws S or otherwise. This plate is recessed upon its rear side to receive the driver-guide, driver, and driver-slide, and has stop-screws S' and S² for limiting, respectively, the upward and the downward motion of said slide.

B is the driver-slide, adapted to have a vertically-reciprocating motion between frame A and front plate, P, its stroke being limited by aforesaid stop-screws S' and S². This slide is formed at its lower end to receive one end of the working-lever, whereby it is operated, and to its upper end the driver is secured.

C² is the driver-channel, formed in the front plate between the front plate cap and driver-guide, described below, and having a thickness corresponding to the thickness of the fasteners, as F, Fig. 5, so that said fastener will very nearly fill said channel in that direction.

D is the driver, secured to and operated by slide B, and fitted to slide in the driver-channel C².

Owing to the thinness of the fasteners used it is found necessary to use a correspondingly-thin driver, which, if it has a rectangular cross-sectional form, is not strong enough to 5 properly endure the work of setting them. For this reason I strengthen said driver by ribs J, Figs. 3 and 4, preferably formed integrally therewith, which are placed one on each edge, preferably, of the front side of the driver, 10 so as not to interfere with the fasteners.

As this machine is more especially designed for setting such button-fasteners as shown at F, Figs. 6 and 7, and as those fasteners have no edge whereby the prong may 15 be kept in a vertical position while the fastener is carried upward through channel C², it is therefore necessary, or at least desirable, to accomplish this by means of a suitable construction of said channel and driver. For 20 this purpose the width of channel C² as measured from right to left in Fig. 3 should only be enough to freely receive the length of head W of the said fastener F, and the upper end of the driver should be made concave or of 25 other shape conforming to the form of the fastener-head, so that the fastener-prong will be maintained in a vertical position by the upward pressure of the conformably-shaped end of the driver on the under side of said 30 fastener-head.

In using the machine the point of the driver does not pass clear up to the top of the driver-channel, but only so far as to drive the fasteners up against the setting-die sufficiently to 35 properly set them. This distance is limited by the stop-screw S'. The downward stroke of the driver is limited by the stop-screw S², by means of which the lower limit of said stroke may be so adjusted that the upper end 40 of the driver shall properly coincide with the bottom of the fasteners in the magazine, hereinafter described. These stops S' S² are not necessarily adjustable ones; but the same may consist of suitable parts of or additions to plate 45 P, constructed so as to limit the stroke of the driver, as explained. It is my intention to cover each of these stops by my claims, whether or not they are made adjustable.

D' is a driver-guide, being a piece formed 50 on or secured to the front plate to fill the space between the ribs J and to guide the point of the driver during its upward stroke, and the fastener which is carried upon said point. I prefer that this driver-guide shall be made of 55 steel, the front plate being of cast-iron, so as to better endure the wear caused by the ascending fasteners.

P' is the front-plate cap, a cap or cover secured, by screws S³ or otherwise, to the rear of 60 the front plate above flange A'. This cap covers the rear side of the recess or channel in said front plate through which the fasteners are driven up by the driver, which channel I call the "driver" channel, and it has a per- 65 foration or mortise, through which fasteners may be fed into the driver-channel above the

driver. This mortise is preferably formed to admit one end either of the magazine or magazine-holder, the latter being the case, as shown in the drawings. Said cap is made separate 70 from flange A' merely to facilitate the construction, adjustment, and repair of the machine, not because that construction of it is necessary. It may also be made integral with plate P, but I consider this undesirable. 75

H is the magazine-holder, which at its front end fits the mortise or opening in plate P', and is supported farther back by the upright A², or otherwise, as may be most convenient. This holder I prefer to make of a channel-bar 80 form adapted to receive the magazine M, which magazine has a groove suitably formed to carry a supply of the fasteners above described. This groove may have any shape suitable to hold said fasteners in place, they being either 85 partially or wholly inclosed, as may be desired; but I prefer the form of groove shown in the drawings. This form is such that when the fasteners are properly placed therein they are held up by the longer end only of their 90 heads. If they are wrongly placed therein, so that the said longer end is outward, they will fall out of the groove. This avoids any danger of accidentally feeding the fasteners to the driver wrong side first, which would cause 95 the prong to be turned over toward the short end of the head.

In Figs. 6, 7, and 8, M is the magazine, having any convenient external form. V is a groove for receiving the prong of the fasteners. V² is a groove for receiving the longer end of the fastener-head W. V³ is a lip or rib having a horizontal width preferably less than the length of said longer end of said head. The horizontal distance from groove 100 V to the edge of rib V³ is then greater than the length of the shorter end of said head. If, now, a fastener, F, is rightly placed in the magazine, as in Fig. 6, the longer end of its head rests on the rib V³, the fastener being 105 thereby held from falling out of the magazine; but if the fastener is wrongly placed therein, as in Fig. 7, the shorter end of the head is not long enough to reach said rib, and is thus allowed to fall out of the channel and out of the 110 way. 115

The magazine M is or may be made of wood, and in this case especially it is more conveniently handled if it does not enter cap P'. On this account a short steel channel, M², Fig. 5, is 120 secured to holder H, forming, if desired, a part thereof, through which the fasteners pass from the magazine to the driver. If the magazine is made of metal, it may be extended into cap P', taking the place of said channel. The 125 fasteners in the magazine are pushed forward toward the driver by a plunger, P², which has preferably a vertical tongue, T, adapted to slide along in groove V behind the fasteners. It is not important what devices are used 130 to operate this plunger provided they do this in a suitable manner, but I prefer to use for

the purpose the improved mechanism which I will now describe.

G is a guide-rod supported by flange A' and bracket A³, parallel to the magazine. On this 5 guide-rod slides the plunger-carrier C, onto the top of which the plunger is formed or secured. This carrier is driven forward by a spring, S⁴, (in this case a push-spring.) It is provided with an arm, E, which fits the groove 10 G², formed in the frame parallel to the guide-rod, and with a handle, H², whereby it is slid back away from the magazine. Its backward motion is limited by a stop, A⁴, on bracket A³.

The construction and arrangement of the 15 carrier-groove G², plunger P², and the magazine are such (see Fig. 10) that when the plunger is in use (being then in front of the magazine) it holds the magazine into its holder H. By this means no other devices except 20 the holder itself are required to properly secure the magazines in place, and hence they may be very quickly removed or put in place. The groove G² is widened at its back end, (see Fig. 9,) and has a lantern-catch, K, formed 25 therein, so that when the carrier C is slid clear back it may be swung on rod G by means of handle H², as shown in Fig. 11, and the lower end of arm E caught into said catch, thereby holding back the carrier and plunger while 30 the operator takes out an empty magazine and puts a full one in its place.

N is the presser-arm, which is pivoted to upright A² by bolt B², has a die, D², formed 35 in its front end directly above the driver, and is operated by links L, pivoted thereto at O². Those links pass down through openings in the frame, and are connected at O to the working-lever R, which lever is pivoted at O² to slide B and at O³ to treadle-rod R², whereby 40 said lever, and thereby the driver and presser, are operated. A stout pull-spring, S⁵, is attached to lever R between O and O² and to the treadle-rod R² at a point some distance down from O². The treadle for operating the said 45 rod is not shown. That spring acts to draw up this rod and hold all the parts connected thereto in the position in which they are shown in Fig. 2. In this position the weight of all 50 those operative parts is sustained by the lower stop-screw, S².

The mode of operation of this machine is as follows: The treadle-rod and the parts connected thereto being in the position shown in Fig. 2, the magazine properly supplied with 55 button-fasteners, and the plunger acting to crowd said fasteners forward, as in Fig. 5, the shoe-upper (or other goods) to which the buttons are to be secured is then placed under the die D², as in Fig. 4. The treadle-rod is 60 then drawn down (slide B continuing down, and pivot O² being the fulcrum of lever R) until the presser-arm brings die D² down firmly onto the aforesaid shoe-upper. At this moment, rod R² continuing to move downward, pivot O becomes the fulcrum of lever R, which lever now acts to raise slide B, (see 65 Fig. 5,) thereby forcing the driver D up

through its channel C² and driving the fastener F, which was above it, up between D' and P' until its prong passes through the shoe-upper, and the eye of a button, suitably held thereabove, is clinched over said eye and formed into a hook by said die D². This operation being completed, the treadle-rod is allowed to rise, returning the driver and die to 75 their original position ready for another operation.

I have not particularly described the construction of die D², because the form required is the same as now commonly used in various 80 well-known instruments for setting other kinds of button-fasteners.

Having now described my invention, what I claim to be new, and therefore desire to secure by Letters Patent of the United States, 85 is—

1. In a button-fastener-setting machine of the class described, a magazine, grooved, substantially as described, to receive the fasteners, and opening into one side of a driver-channel above a driver, a driver-channel adapted to receive the fasteners one at a time from said magazine, and corresponding to them, substantially as described, a die above said channel adapted to bend over into a hook 95 the prongs of said fasteners, and a driver having a reciprocating motion in said channel, and having its point conformably shaped to the fastener-head, whereby said fasteners are driven, with their prongs maintained vertically, from their point of entrance into said channel through the same and against said die, combined and operating substantially as set forth.

2. In a button-fastener-setting machine of the class described, a magazine, grooved, substantially as described, to receive the fasteners, and opening into one side of a driver-channel above a driver, a driver-channel adapted to receive the fasteners one at a time 105 from said magazine, and corresponding to them, substantially as described, a die above said channel adapted to bend over into a hook the prongs of said fasteners, and a driver having a reciprocating motion in said channel, and having its point conformably shaped to the fastener-head, whereby said fasteners are driven, with their prongs maintained vertically, from their point of entrance into said channel through the same and against said 110 die, and an actuating mechanism, substantially as described, for operating said driver and die, combined and operating substantially as set forth.

3. In a button-fastener-setting machine of 125 the class described, a magazine, grooved, substantially as described, to receive the fasteners, and opening into one side of a driver-channel above a driver, a driver-channel adapted to receive the fasteners one at a time from said 130 magazine, and corresponding to them, substantially as described, a die above said channel adapted to bend over into a hook the prongs of said fasteners, and a driver having a recip-

- roating motion in said channel, and having its point conformably shaped to the fastener-head, whereby said fasteners are driven, with their prongs maintained vertically, from their 5 point of entrance into said channel through the same and against said die, and the lever mechanism, substantially as described, adapted to first press down said die and then throw up the driver, combined and operating substantially as set forth.
4. In a button-fastener-setting machine, slide B, having thereon a driver, as D, a vertically-movable presser, N, having die D², lever R, links L, rod R², and spring S², combined and operating substantially as set forth.
5. In a button-fastener-setting machine, a button-fastener driver, D, having one or more flanges, J, in combination with driver-guide D', forming one side of the driver-channel, substantially as described.
6. A magazine for holding button-fasteners the heads of which are longer on one side of the prong than on the other side thereof, having groove V, groove V², and rib V³, said rib being so formed as to retain said fasteners in the magazine only when the longer ends of their heads are in said groove V², substantially as described.
7. In a button-fastener-setting machine, magazine-holder H, magazine M, removably fixed on said holder and grooved to receive the button-fasteners, and plunger P², having a tongue adapted to slide in said groove, combined and operating substantially as described.
8. In combination, a magazine-holder, a removable magazine supported by said holder, a guide-rod parallel to the groove of said magazine, a plunger-carrier sliding on said guide-rod, having a plunger adapted to prevent said magazine from leaving its place and to feed button-fasteners through the same, and a spring arranged to slide said carrier on said rod, substantially as described.
9. In combination, magazine M, guide-rod G, carrier C, having plunger P² and arm E, and adapted to have a sliding and swinging motion on said rod, and groove G², substantially as and for the purpose described.
10. In combination, magazine M, suitably supported in a fixed position, guide G, carrier C, having plunger P² and arm E, and adapted to have a sliding and a swinging motion on said guide, groove G², having catch K, and spring S⁴, substantially as and for the purpose described.
11. In a button-fastener-setting machine, in combination, a magazine-holder, H, having the short channel M², and magazine M, removably fitted to said holder, substantially as described.
12. In combination, plate P, recessed to receive slide B and driver D, cap P', forming one side of the driver-channel, and having an opening for a channel or magazine, M² or M, a channel or magazine, as M² or M, fitted to said opening, and a stop, as S², determining the lower limit of the stroke of said driver, so that the upper end of the driver will coincide with the bottom of the button-fasteners in said magazine, substantially as described.
13. In combination, plate P, recessed to receive slide B and driver D, cap P', forming one side of the driver-channel, and having an opening for a channel or magazine, a channel or magazine, as M² or M, fitted to said opening, and a stop, as S², determining the upper limit of the stroke of said driver, so that it will drive the fasteners up against said die the distance only which is required to properly set them, substantially as described.
14. In a button-fastener-setting machine, in combination, plate P, recessed to receive slide B and driver D, cap P', forming one side of the driver-channel, and having an opening for a channel or magazine, as M² or M, a channel or magazine, as M² or M, fitted to said opening, a stop determining the lower limit of the stroke of said driver, so that the upper end of the driver will properly coincide with the bottom of the button-fasteners in said magazine, a die, D², suitably held above the top of said channel, and a stop determining the upper limit of the stroke of said driver, so that it will drive the fasteners up against said die the distance only which is required to properly set them, substantially as described.
15. In a button-fastener-setting machine, the magazine M, grooved to receive fasteners F, substantially as described, in combination with a sliding plunger, P², formed to enter and feed said fasteners through said magazine, substantially as set forth.
